Application August 17, 1950, Serial No. 11,818

Term of patent 14 years

(Cl. D91—1)

To all whom it may concern:

Be it known that we, William C. Wehner and Jacob Lapp, both citizens of the United States of America, residents of the city of Grosse Pointe Park, and the city of Detroit, respectively, in the county of Wayne, State of Michigan, have invented a new, original, and ornamental Design for a Lawn Sprinkler, of which the following is a specification, reference being had to the accompanying drawing, forming part thereof.

Figure 1 is a side elevation of a lawn sprinkler, embodying our new design;

Figure 2 is a front elevation; and

Figure 3 is a perspective from the same side as Figure 1.

The dominant features of the design are shown in full lines.

We claim:

The ornamental design for a lawn sprinkler, as shown and described.

WILLIAM C. WEHNER.
JACOB LAPP.
